Patented May 30, 1967

207,789

LUMINAIRE

Thomas E. Kimble, Pataskala, Ohio, assignor to Holophane Company, Inc., New York, N.Y., a corporation of Delaware

Filed Aug. 16, 1966, Ser. No. 3,491

Term of patent 14 years

(Cl. D48—23)

T1 1.

FIG. 1.

FIG. 1 is a perspective view of the luminaire of the invention;

FIG. 2 is an elevational view of the luminaire, partially broken away to show the internal design in elevation and cross section; and

FIG. 3 is a top view of the luminaire.

I claim:

The ornamental design for a luminaire, substantially as shown and described.
